UNITED STATES PATENT OFFICE.

GASTON A. BRUNELLE, OF SAN FRANCISCO, CALIFORNIA.

CENTER PUNCH.

Application filed June 29, 1925. Serial No. 40,324.

The present invention relates to improvements in center punches for marking the center of a piece of work to be drilled centrally.

5 The general object of the invention is to provide a tool for facilitating the operation of definitely locating and marking the central or axial line of a piece of work, such as a piece of machinery shafting or the like.

10 The above and other objects are accomplished by instrumentalities pointed out in the following specification.

The invention is clearly defined in the claims.

15 A satisfactory embodiment of the invention is illustrated in the accompanying drawings forming part of the specification and in which—

Figure 1 is a plan view of the body portion of the tool without the table support.

20 Figure 2 is a side elevation of the tool in use.

Figure 3 is a sectional detail on the line 3—3 of Figure 1, looking in the direction of 25 the arrows, and

Figure 4 is a view similar to Figure 3, but taken through the central portion of the body, on the line 4 of Figure 1.

The body *a* of the tool is provided with a 30 vertically extending work receiving passage 5 which is in open communication and centered with a guide opening 6 through which the punch 7 is slidable into contact with the work 8. The passage 5 is disposed centrally 35 of a horizontally arranged fixed base plate 9, the upper face of which has a circular rabbet 10 for confining the spur gear wheel in the form of an annulus 11. The gear wheel 11 is rotated by a toothed pinion 12 to transmit 40 motion to a series of pinions 13 spaced apart for equal distances and meshing with gear wheel 11. The pinions 13 are supported for rotation upon shouldered spindles secured in sockets in the upper face of base plate 9, 45 one of these spindles being shown in Figures 2 and 3 and indicated by 14. The shouldered spindles are constructed and arranged so as to support pinions 13 so that their teeth mesh with the gear wheel 11 and with racks 50 15 disposed above the gear wheel 11. The racks 15 are arranged horizontally and reciprocate a plurality of arms 17 to the lower faces of which they are secured by screws 16. A circular shaped upper plate 18 arranged 55 above base plate 9 is held in spaced relation thereto by spacer sleeves 19 through which

pass bolts 20 for connecting the base and upper plates together, the bolts being secured by the usual nuts 21. The guide opening 6 is disposed centrally of upper plate 18 and extends vertically and communicates with a plurality of radially disposed dovetailed guide recesses 22 in the lower face of upper plate 18. The recesses 22 are provided for the reception of the arms 17, the sides of which are beveled to conform to the recesses 22 so as to slide therein. The long dimensions of the arms are such as permit the inner ends of the arms to be moved to the centers of the passage 5 and guide opening 6 without liability of disengagement between the arms and their grooves or disengagement between the racks and their respective openings. The several pinions 13 are uniform in size and in number of teeth and so too are 75 racks 15, so that a movement on the part of pinion 12 is transmitted to the several arms simultaneously and causes these to move synchronously and for corresponding distances. A hand wheel 23 at one end of a shaft 24 rotates the latter to turn in a bearing in upper plate 18 through which shaft 24 extends, the lower end of shaft 24 being fixedly secured to pinion 12, and journaled in a socket in base plate 9, as shown in Figure 2.

Punch 7 is slidable in a vertically disposed sleeve 25 which is carried by a base plate 26 superimposed upon upper plate 18 and adjustable laterally by a plurality of set screws 26' extending through screw threaded 90 openings in upright lugs 27 upon the upper plate and into sockets 28 in the base portion 26. The provision of this construction permits of adjusting the pointed lower end of punch 7 into the center of guide opening 6 regardless of offsetting on the part of the point with respect to the axis of the punch which frequently results from defective grinding, burring and the like. The adjusting screws are locked by nuts 29 and the base portion 26 is locked in any of its adjusted 100 positions by clamp screws 30 extending through enlarged chambers 31 in base portion 26 and screwed into the upper plate 18, said screws also extending through washers 105 32 disposed over the upper ends of the chambers 31. The interior of sleeve 25 is provided with a longitudinal groove 33 for the reception of a pin 34 carried by the punch 7 to prevent rotation of the punch and possible 110 decentering of the point thereof.

In Figure 2, the body *a* is shown sup-

ported on the top 35 of a table whose legs are indicated by 36. In this instance the base plate 9 is secured to top 35 by bolts 37. A central opening 38, indicated by dotted lines, alines with the passage 5 and is disposed over a carrier 39 having a centrally tapered seat 40 for the reception of the lower end of the piece of work 8. A plurality of flexible hangers 41 are secured 10 at one end to opposite portions of the carrier 39 and are trained around sheaves 42 and connected to counter-weights 43. Brackets 44 depending from opposite portions of the top 35 support the sheaves 42 and the long dimensions of the hangers 41 and legs 36 are such that the weights 43 may elevate the carrier to points opposite the sheaves 42.

In using the device just described, the 20 operator proceeds by lowering the carrier 39 manually and then directing the work 8 up through the opening 38 and passage 9. If additional down pull is found necessary to hold the work elevated, then suitable additional weights, such as those used with a beam scale, may be applied. When the work 25 is thus supported by carrier 39, operating handle 23 is turned to move arms 17 inwardly until the inner ends of said arms make contact with spaced portions on the 30 surfaces of the work 8. The sloping of the wall of seat 40 enables the work to readily assume a vertically upright position. When the parts are so positioned, the projecting upper end of punch 7 is given a 35 blow with a hammer, whereupon the pointed lower end makes the required mark in the center of the adjacent end of the work.

Although I have shown and described one 40 embodiment of my invention, it is to be understood that the same is susceptible of various changes; and I reserve the right to employ such as may come within the scope 45 of the appended claims.

I claim:

1. A center punch comprising a body having a vertically extending passage for receiving the work to be punched, a slidable punch extending vertically downward into 50 the passage and disposed in alinement with

the center thereof, a plurality of arms arranged in angular relation and slidable radially toward and away from the center of the passage, means for operating said arms to slide simultaneously and synchronously 55 into contact with spaced lateral portions of the work and thereby center the same with the punch, and gravity actuated means engaging the lower end of the work and supporting the same vertically between said 60 arms.

2. A center punch comprising a body having a base member provided with a centrally disposed vertically extending passage for receiving the work to be punched, an upper 65 member disposed above and arranged in spaced relation to the base and having a vertically disposed guide centered with the passage of the base, a punch slidably mounted in said guide and extendible into the passage of the base and into contact with the center of the work arranged therein, at least three arms arranged in angular relation and slidable radially toward and away from the center of the passage and disposed between 70 the base and the upper member, and means for operating said arms to slide simultaneously and synchronously into contact with spaced portions of the work to be punched and thereby center the same with the punch. 75

3. A center punch comprising a body having a base member provided with a centrally disposed vertically extending passage for receiving the work to be punched, an upper member disposed above and arranged 80 in spaced relation to the base and having a vertically disposed guide centered with the passage of the base, a punch slidably mounted in said guide and extendible into the passage of the base and into contact with the center of the work arranged therein, at least three arms arranged in angular relation and slidable radially toward and away from the center of the passage and carried by the said upper member, and means for 85 operating said arms to slide simultaneously and synchronously into contact with spaced portions of the work to be punched and thereby center the same with the punch. 90
